UNITED STATES PATENT OFFICE.

WILLIAM D. THOMPSON, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,101,820.

Specification of Letters Patent. Patented June 30, 1914.

Application filed October 13, 1910. Serial No. 536,854.

To all whom it may concern:

Be it known that I, WILLIAM D. THOMPSON, a citizen of the United States of America, residing at Detroit, in the county of

5 Wayne and State of Michigan, have invented certain new and useful Improvements in Car-Roofs, of which the following is a specification, reference being had therein to the accompanying drawings.

10 The invention relates to car roofs, more particularly to the construction of the carlines and means for securing the same to the purlins, as hereinafter set forth.

In the drawings—Figure 1 is a cross section through the car roof. Fig. 2 is a sectional perspective view of one of the carlines. Fig. 3 is a cross section of the carline on line α — α Fig. 1. Fig. 4 is a sectional perspective view of the carline viewed from 20 the inner side.

My improved roof structure comprises carline beams which are formed up from sheet metal.

It is an object of the invention to secure 25 the maximum strength with a minimum depth or thickness to the roof structure, to this end the carlines are formed as follows: In cross section the beam has a central inverted U shaped portion A which is the full 30 depth of the roof, and upon opposite sides of this central portion are reversely bent U portions B extending only a part of the depth of the central portion and preferably terminating in outwardly extending horizontal 35 flange portions C. At the point in the length of the beam at which the purlins cross, the reversely bent U portions are flattened into a plane adjacent to the flanges C, thereby forming a recess D for receiving the 40 purlins. This recess is preferably of a depth equal to the thickness of the purlin so that the latter is confined within the vertical space limits of the carline.

The carline constructed as described is 45 adapted to support the roofing plates (not shown) upon the flanges C, and these flanges are in substantially the plane of the upper

face of the purlins, which latter also support the roof plates, thus the whole structure is limited in depth to the vertical section of 50 the carline.

What I claim as my invention is,—

1. In a car roof, a carline formed from sheet metal with a longitudinal central return-bent portion the full depth of the roof, 55 and an adjacent oppositely bent portion of the depth of the purlin, said oppositely bent portion being flattened at one point to form a recess for receiving the purlin.

2. In a car roof, a carline formed of sheet 60 metal comprising a longitudinal central return-bent portion, outer oppositely return-bent portions extending only a part of the depth of said central portion and terminating in outwardly extending horizontal 65 flanges, the section of said beam below said horizontal flanges being flattened at the point of intersection with the purlin to form a recess for receiving the latter.

3. In a car roof, a carline formed of sheet 70 metal, comprising a central inverted trough-shaped portion, adjacent oppositely bent trough-shaped portions extending only a part of the depth of said central portion and terminating in outwardly extending horizontal 75 flanges, the section of said beam below said horizontal flanges being flattened at the point of intersection with the purlin to form a recess for receiving the latter.

4. In a car roof, a carline formed from 80 sheet metal having a longitudinal central return-bent portion, oppositely return-bent outer portions extending only a part of the depth of the central portion and terminating in outwardly extending horizontal portions, 85 said return-bent portions having a part thereof flattened into a plane adjacent the outwardly extending horizontal portions.

In testimony whereof I affix my signature in presence of two witnesses.

WILLIAM D. THOMPSON.
